ABSTRACT OF THE DISCLOSURE

A punching apparatus for the cylindrically curved flanges of brakeshoes in which a pair of mating die holders having convex faces receive the web or flange of a brakeshoe and a die holder having a concave face cooperates with the convex die holders to clamp the rim of the brakeshoe; the die holders being provided with radiating sets of punch dies which are operated progressively by an eccentric roller.

SUMMARY OF THE INVENTION

In the forming of rivet holes or holes for any other purpose in a hollow cylindrical or semi-cylindrical structure, such as a brakeshoe, the holes are formed prior to shaping the structure into its cylindrical form or the holes are formed one-at-a-time by moving the workpiece past a single punch die. The present invention is to provide an apparatus for punching as many rivet holes or the like as needed in a cylindrical work without moving the workpiece and included in the objects of the invention are:

First, to provide an apparatus of this type in which a cylindrical or semi-cylindrical workpiece is clamped by semi-cylindrical die holders containing a set of dies arranged radially and an eccentric roller driven by a shaft (located at the intersection of the set of radii) operates the dies progressively.

Second, to provide an apparatus of this type particularly adapted to punch rivet holes in brakeshoes wherein the brakeshoe flange is held between one pair of die holders and the rim is held between these die holders as a unit and a third die holder.

Third, to provide an apparatus of this type wherein means are provided to move the die holders into clamping engagement for the punching operation or to separate them for insertion of a workpiece; the apparatus incorporating means whereby the die holders are locked in place to prevent relative movement under the forces inherent in the punching operation.

DESCRIPTION OF FIGURES

FIGURE 1 is a front view of the brakeshoe punching apparatus with the die in its closed position.

FIGURE 2 is a side view thereof, also with the die in its closed position.

FIGURE 3 is an enlarged fragmentary sectional view, taken through 3—3 of FIGURE 2, showing the drag brake.

FIGURE 4 is a partial sectional, partial front view, taken through 4—4 of FIGURE 6, showing the die in its open position.

FIGURE 5 is a fragmentary sectional view, taken through 5—5 of FIGURE 6, showing the die in its closed position.

FIGURE 6 is an enlarged fragmentary sectional view, taken through 6—6 of FIGURE 1, showing the die in its open position.

FIGURE 7 is a sectional view, taken through 7—7 of FIGURE 5, with the punch actuator omitted and with the upper die shown fragmentarily.

2

FIGURE 8 is an enlarged fragmentary sectional view, taken through 8—8 of FIGURE 1, with the die in its closed position and showing one of the die units.

FIGURE 9 is an enlarged fragmentary sectional view, taken through 9—9 of FIGURE 4, with the die shown in its closed position and showing one of the alignment pins.

FIGURE 10 is an enlarged fragmentary sectional view, taken within circle 10 of FIGURE 1, showing a pressure pin.

FIGURE 11 is an enlarged fragmentary sectional view, taken through 11—11 of FIGURE 1, with the die shown in its closed position and showing a pair of opposed positioning and clamping pins.

FIGURE 12 is an enlarged fragmentary sectional view, taken through 12—12 of FIGURE 18, showing the clutch dog.

FIGURE 13 is a fragmentary sectional view, taken through 13—13 of FIGURE 12.

FIGURE 14 is an enlarged fragmentary sectional view, taken through 14—14 of FIGURE 18.

FIGURE 15 is a perspective view of the clutch dog.

FIGURE 16 is an enlarged fragmentary partially sectional, partially side view of the clutch mechanism, taken within circle 16 of FIGURE 2.

FIGURE 17 is a fragmentary sectional view, taken through 17—17 of FIGURE 16.

FIGURE 18 is a fragmentary sectional view, taken through 18—18 of FIGURE 16.

FIGURE 19 is a fragmentary sectional view, taken through 19—19 of FIGURE 16.

For purposes of illustration, the apparatus is shown as arranged for the punching of rivet holes in a brakeshoe. The conventional brake shoe S includes a semi-cylindrical rim R from which extends a radially inwardly directed flange F.

The apparatus includes a table 1, on which is mounted a vertically disposed front plate 2, and a back frame 3 connected by horizontal beams 4.

Mounted near lateral sides of the front plate at the forward side thereof is a pair of vertically extending guide bars 5. Slidably mounted between the guide bars, by means of guide sleeves 6, is a backing block 7, having an upwardly directed concave face 8. The bottom end 45 of the backing block 7 is joined by a yoke 9 to a piston rod 10 extending from a hydraulic power unit 11, supported by a frame 12, suspended under the table 1.

Mounted within the concave face 8 of the backing block 7, is a concave or semi-cylindrical die holder 13. The die holder is secured in place by means of vertical retaining pins 14 and horizontal retaining screws 15. It is intended that a set of die holders be provided, having different internal diameters, but interchangeably retainable in the backing block by the pins 14 and the screws 15.

The die holder 13 is provided with a set of radially extending die receiving bores 16 which may be in the same plane or in different planes depending upon the desired location of the rivet holes to be formed in the brakeshoe rim. Each bore 16 receives a die collar or female die 17.

60 The die receiving bores communicate with a chip receiving channel 18, which in turn communicates with one or more outlet openings 19.

Secured to the upper portion of the front plate 2, in vertical alignment with the concave die holder 13, is a fixed convex die holder 20. The die holder 20 is secured by mounting bolts 21, and in addition, is held against displacement by backing blocks 22. The fixed convex die holder 20 is approximately half the axial dimension of the concave die holder 13.

A second convex die holder 23, having dimensions similar to the die holder 20, is located in front of the die holder 20. The die holder 23 is supported relative to the

die holder 20 by means of horizontal guide pins 24. The die holder 23 is also supported by a cross bar 25, secured to the lateral margins of the front plate 2. The horizontally movable die holder 23 is connected by a yoke 26, to a piston rod 27 extending from a hydraulic power unit 28 secured to the cross bar 25.

The die holders 20 and 23 are provided with radial die bores 29, each containing a male die unit 30. Each die unit includes a guide bushing 31 at the radially outer end of the corresponding die bore, which is held in place by screws 32. Each guide bushing slidably receives a die pin 33 which is provided at its radially inner end with a head 34. A return spring 35 is interposed between the bushing 31 and the head 34, all as shown best in FIGURE 8. The male die units are so located that when the concave die holder 13 and the two convex die holders 20 and 23 clamp the rim R of a brakeshoe S therebetween, each die pin 33 is in axial alignment with the corresponding die collar 13. The head 34 of each punch die unit protrudes radially inward into a semi-circular recess 36 formed in each die holder 20 and 23; that is, each die holder is in the form of a hollow semi-cylinder.

A drive shaft 37 is located with its axis coinciding with the points of intersection of the various punch die units. The drive shaft is supported in a pair of ball bearings 38 located in the upper portion of the front plate 2, and the back frame 3. In addition, the drive shaft is supported in a sleeve bearing 39 provided in a mounting block 40, carried by the backing blocks 22. Between the forward ball bearing 38 and the sleeve bearing 39, the shaft is provided with a pair of eccentric rollers 41. Each eccentric roller includes an eccentric mounting collar 42 and a roller bearing, having an inner race 43, rollers 44 and an outer race 45. The outer race forms a pressure ring, which when the roller moves eccentrically, bears against the heads 34 of the punch die units.

The confronting sides of the die holders 20 and 23 define a brakeshoe flange slot 46. This slot is intersected by opposed positioning and clamping pins 47, backed by springs 48. The pins 47 permit a brakeshoe to be thrust manually and be held in place until the concave die holder has been raised into operating relation with the die holders 20 and 23.

It is preferred that the brakeshoe not be pressed fully into place by manual operation. Instead, a pair of radially extending pressure pins 49 are provided, which are backed by springs, preferably in the form of Bellevue washers, 50, as shown in FIGURE 10. When the die holder 13 is moved away from the die holders 20 and 23, the pressure pins force the brakeshoe rim R a short distance away from the holders 20 and 23, so that the brakeshoe may be manually engaged for removal.

Inasmuch as it is essential that both die holders 20 and 23 be in proper radial alignment with the die holder 13, the die holder 20 is accurately positioned by alignment pins 51, indicated in FIGURE 9, and the die holder 23 is properly located radially by its horizontal guide pins 24 and its abutment contact with the die holder 20.

In order to assure that the die holder 13 is in place, and will not move in response to any force exerted by the die pins 33, a pair of locking bars 52, shown best in FIGURE 7, are movable horizontally through the front plate 2 and into sockets 53 provided in the die holder 13. The locking bars 52 are connected by a crossbar 54 which in turn is joined by a pair of links 55 to a lever 56, pivotally supported by a bracket 57. The lever 56 is connected to a piston rod 58 extending from a hydraulic power unit 59.

The drive shaft 37 is operated by a drive motor 60, connected through a belt 61 to a gear reduction unit 62, which in turn is connected by a belt 63 to a flywheel 64 mounted on the shaft 37 behind the back frame 3, as indicated in FIGURE 2.

The flywheel is provided with a clutch collar 65, indicated in FIGURES 12, 13, 16 and 19. The collar 65 is provided with a clutch slot 66 which is engaged by a clutch

dog 67. The clutch dog is carried by a clutch collar 68 mounted on the shaft 37. The clutch dog is slidably mounted in a socket 69 and backed by a spring 70. The outer end of the dog is beveled to form a latch tip 71 which confronts the clutch collar 65 to engage the notch 66, as indicated best in FIGURE 12. Outward movement of the clutch dog is restrained by a stop plate 72 which fits within a recess 73 and is held there by a retainer clip 74. The stop plate also restrains the clutch dog against rotation in its socket 69.

The clutch dog is provided with a side slot 75, having a cam surface 76. The clutch collar 68 is provided with an annular channel 77 which exposes the side slot 75 and receives a tip 78 of a trip bar 79 suitably supported on the back frame 3 by a guide plate 80. The trip bar is connected to a lever 81 which is urged by a spring 82 in a direction to urge the tip 78 of the trip bar into the side slots 75. The lever 81 is suitably connected, by means not shown, to an operating handle 83 mounted at one side of the front plate 2.

In order to control overtravel of the shaft 37, a drag brake 84 is provided, as shown best in FIGURE 3. The drag brake includes a pair of clamp members 85 which fit over opposite sides of the shaft and are pivotally connected to a common mounting boss 86. The clamp members are also joined by a tie bolt 87 which carries a spring 88. The confronting sides of the clamp members 85, which are semi-cylindrical, are provided with brakeshoes 89 which engage a collar 90 secured to the shaft 37.

Operation of the brakeshoe punching apparatus is as follows:

The brakeshoe flange slot 46 is profiled so as to correspond to the flange of a particular style of brakeshoe. Thus, a brakeshoe having the proper flange profile is inserted between the die holders 20 and 23 when the die holders are slightly separated. The brakeshoe is held in place by the clamping pins 47. The die holder 13 is then thrust upwardly to clamp the rim R against the radially outer surfaces of the die holders 20 and 23. Prior to this, the die holder 23 is closed against the die holder 20. It is not intended by this operation to clamp the flange F tightly, as variations in the thickness of the flange would prevent proper axial alignment of the punch die components. When the rim is properly clamped, the operating handle 83 is moved to cause release of the clutch dog 67 from the tip 78 so that the latch tip 71 can engage the slot 66 whereupon the flywheel rotates the shaft 37 and causes the outer races or pressure rollers 45 to engage the heads 34 of the punch die units 30. Such engagement stops the pressure roller from rotating with the shaft, but does cause the pressure roller to move radially in an eccentric path so that the die pins 33 are forced radially outward and in a progressive manner causing the actual punching of the holes to occur in rapid sequence rather than simultaneously. When the punching operation is complete, the cam surface 76 is engaged by the tip 78 of the trip bar and the dog is retracted, whereupon the drag brake quickly stops further rotation of the shaft 37.

The die holder 13 is then retracted. First, however, releasing the locking bars 52. Also, the die holder 23 is removed a short distance from the die holder 20. This movement may be sufficient that the clamping pins 47 disengage the brakeshoe flange F so that the brakeshoe may drop free, aided by the action of the pressure pins 49.

While particular embodiments of this invention have been shown and described, it is not intended to limit the same to the details of the constructions set forth, but instead, the invention embraces such changes, modifications and equivalents of the various parts and their relationships as come within the purview of the appended claims.

I claim:

1. An apparatus for punching apertures in workpieces of cylindrical form, comprising:
(a) mating radially inner and radially outer die holders defining a cylinder;

- (b) means for forcing said die holders into clamping engagement with a correspondingly contoured workpiece therebetween;
  - (c) a set of punching dies extending radially with respect to said die holders, each die having a moving component disposed in said radially inner die holder and a mating component in said radially outer die holder;
  - (d) and operating means for moving the movable components of said dies radially to penetrate said workpiece.
2. An apparatus, as defined in claim 1, wherein:
- (a) said operating means includes a rotatable shaft radially inward of said punching dies and an eccentric roller mounted thereon and having an outer pressure ring for operating said punching dies.
3. An apparatus, as defined in claim 1, wherein:
- (a) a pair of radially inner die holders is provided, movable as a unit with respect to said outer die holder;
  - (b) and means effecting relative movement of said inner die holders perpendicular to the relative radial movement of said inner and outer die holders, thereby to receive therebetween a workpiece having a radially extending flange.
4. An apparatus, as defined in claim 1, which further comprises:
- (a) means operable independently of said clamping means for locking said outer die holder against displacement by the force exerted on operation of said punching dies by said operating means.
5. An apparatus for punching rivet holes in brakeshoes, comprising:
- (a) a radially outer concave die holder;
  - (b) a radially inner convex die holder;
  - (c) a set of punching dies having radially movable inner components disposed in said inner die holder, and fixed outer die components disposed in said outer die holder;
  - (d) means for effecting relative movement of said die holders to clamp the rim of a brakeshoe therebetween;
  - (e) and operating means for effecting radial movement of said movable die components to punch said rim.
6. An apparatus, as defined in claim 5, wherein:
- (a) said operating means includes a shaft having an axis passing through the point of intersection of the axes of said set of punching dies, and an eccentric roller progressively engageable with said movable die components to operate said dies in sequence.
7. An apparatus, as defined in claim 5, wherein:
- (a) a pair of inner die holders disposed on opposite sides of said brakeshoe flange are provided and are radially movable to and from said flange;
  - (b) and two sets of said dies are provided for punching said rim on opposite sides of said flange.
8. An apparatus, as defined in claim 7, which further comprises:
- (a) means for locating said inner die holders and said outer die holder in predetermined cooperative position to align each pair of die components for a punching operation.
9. An apparatus, as defined in claim 5, which further comprises:
- (a) means locking said outer die holder in predetermined relation to said inner die holder against displacement by the force exerted during operation of said punching dies.
10. An apparatus for punching apertures in work-

- pieces defining at least a portion of a cylinder, said apparatus comprising:
- (a) an operating shaft located at the axis of said workpiece;
  - (b) at least one eccentric pressure ring journalled on said shaft, said shaft being rotatable in said ring to cause a progressive radial extension and retraction of the surface of said ring;
  - (c) an inner die holder of arcuate form, having a radially inner side confronting said pressure ring;
  - (d) a plurality of radially movable punching die elements mounted in said die holder and having radially inner ends engageable in sequence by said pressure ring to effect radial movement of said dies;
  - (e) a radially outer die holder having a concave side confronting the radially outer side of said inner die holder;
  - (f) means for moving said die holders radially for clamping said workpiece between said die holders;
  - (g) and fixed die elements in said outer holder adapted to be aligned with said movable die elements when said work piece is clamped.
11. An apparatus, as defined in claim 10, wherein:
- (a) said inner die holder is fixed and mounted above said outer die holder;
  - (b) said moving means is a hydraulic power unit to reciprocate said outer die holder;
  - (c) and means independent of said moving means locks said outer die holder in position to place said die elements in radial alignment.
12. An apparatus, as defined in claim 10, wherein:
- (a) a second inner die holder is mounted in axial alignment with the first die holder for movement relative thereto.
13. An apparatus, as defined in claim 12, wherein:
- (a) said first inner die holder is fixed, said second inner die holder moves axially relatively thereto and said inner die holders are adapted to receive a radially extending portion of a workpiece therebetween;
  - (b) said outer die holder moves radially with respect to both inner die holders;
  - (c) a set of radially movable die elements is contained in each of said inner die holders;
  - (d) and two mating sets of die elements are carried by said outer die holder.
14. An apparatus, as defined in claim 10, wherein:
- (a) means is provided to effect a single rotation of said shaft.
15. An apparatus, as defined in claim 13, which further comprises:
- (a) axially movable yieldable clamping means carried by said inner die holders for engaging and holding the flange of the brakeshoe prior to engagement of said outer die holder, said yieldable clamping means adapted to release said flange on axial separation of said inner die holders.
